DRAPERY TRACK

Ellis I. Toder, 9225 Grace Lane,
Philadelphia, Pa. 19115

Filed June 24, 1968, Ser. No. 12,493

Term of patent 14 years

Int. Cl. D8—03

U.S. Cl. D8—208

Fig. 1.

Fig. 2.

FIGURE 1 is a perspective view from the left front and below of my new design of drapery track;

FIGURE 2 is a perspective view from the rear and below of my new design of drapery track shown in FIGURE 1;

FIGURE 3 is an end elevation of my new design of drapery track as would be seen when viewed along the lines 3—3 of FIGURE 1, the opposite end elevation being identical but reversed left for right;

FIGURE 4 is a front elevational view of my new design of drapery track as would be seen when viewed along the line 4—4 of FIGURE 3;

FIGURE 5 is a bottom plan view of my new design of drapery track as would be seen when viewed along the line 5—5 of FIGURE 3;

FIGURE 6 is a rear elevational view of my new design of drapery track as would be seen when viewed along the line 6—6 of FIGURE 3; and

FIGURE 7 is a top plan view of my new design of drapery track as would be seen when viewed along the line 7—7 of FIGURE 3.

I claim:

The ornamental design for a drapery track, as shown and described.
